WILLIAM B. GREEN, OF MAYFIELD, NEW YORK.

Design No. 4,923, dated May 23, 1871.

DESIGN FOR A GLOVE.

The Schedule referred to in these Letters Patent and making part of the same.

To all whom it may concern:

Be it known that I, WILLIAM B. GREEN, of Mayfield, in the county of Fulton and State of New York, have invented a new and original Design for a Glove-Pattern; and I do hereby declare that the following is a full, clear, and exact description thereof, which will enable others skilled in the art to make and use the same, reference being had to the accompanying drawing forming part of this specification, in which—

Figure 1 represents a face view of my new design for a pattern.

Figure 2 is a face view of the pieces which make up the glove, showing them put together ready for sewing.

Similar letters of reference indicate corresponding parts.

This invention relates to a new form of pattern for the palm piece of a glove, and consists in forming

thereon, in line with the forefinger, the piece which constitutes the inner side of the thumb.

A in the drawing represents the palm piece of the glove, provided with the projections *a*, *b*, *c*, and *d*, for the four fingers, and with an attachment, *e*, for the inner side of the thumb.

An aperture, *f*, is cut through the palm piece at the root of the thumb attachment, and in order to furnish the upper concave seam between thumb and palm when the piece *e* is folded against the palm, as in fig. 2.

B and C are the other pieces of the glove.
I claim as my invention—

The design for a glove-pattern, A, as shown.

WM. B. GREEN.
